UNITED STATES PATENT OFFICE.

MILON J. TRUMBLE, OF ALHAMBRA, CALIFORNIA.

SOUND REPRODUCER.

Application filed April 25, 1921. Serial No. 464,170.

To all whom it may concern:

Be it known that I, MILON J. TRUMBLE, a citizen of the United States, residing at Alhambra, county of Los Angeles and State of California, have invented a new and useful Improvement in Sound Reproducers, of which the following is a specification.

My invention relates to the reproduction of sound and is particularly applicable to the reproduction of sound from phonograph records.

Referring to the drawing which is for illustrative purposes only,

Fig. 1 is a side elevation of my invention when applied to a disc record in which the sound record is formed on the side of the groove.

Fig. 2 is a section on a plane represented by the line 2—2 of Fig. 1, and,

Fig. 3 is a section on a plane represented by the line 3—3 of Fig. 1.

In the form of the invention shown, a supporting structure 11 is provided in which a sound chamber 12 is formed, the front of this sound chamber being closed by a main diaphragm 13 and the back of this sound chamber having an opening 14 through which the sound passes into a tone arm 15.

Mounted on pivots 20 on the structure 11 by means of screws 21 is a stylus holder 22 which has a socket in which the stylus or needle 23 may be placed, this needle being clamped therein by means of a screw 24.

The stylus holder 22 extends up and is provided with a round end 25 having a facing of rubber or similar material which presses against the center of the diaphragm 13. Extending through an opening 30 in the stylus holder 22 is one end of a cross lever 31, this cross lever being mounted on pivots 32 which are parallel to the stylus holder 22. The other end 33 of the cross lever 31 carries a screw 34, the rounded end of which presses against a drum diaphragm 35 which closes the front of an auxiliary chamber 36, such chamber having a relief opening 37 in the back thereof.

It will be noted that the cross lever 31 is substantially at right angles to the stylus holder 22 which is thus restrained from any movements parallel to the diaphragm 13 and at right angles to the stylus holder 22. By

restraining the stylus holder in this manner, I eliminate a great deal of the scratchy sound produced by ordinary reproducers. The screw 34 is set up until the drum diaphragm 35 exerts considerable pressure between the end 25 of the stylus holder 22 and the main diaphragm 13. I have found that the diaphragm 13 may be conveniently made of mica and that the drum diaphragm 35 may be conveniently made of very thin metal. I have also found that it is preferable to make the drum diaphragm 35 and the main diaphragm 13 of different diameters so that they will have different periods of vibration. The reproduced sound is improved by placing an anvil in the sound chamber 12 and I prefer to use a conical shaped anvil 46 suspended in such chamber at three points by means of screws 47. The anvil 46 is provided with an opening 48 extending therethrough at right angles to the diaphragm 13, the face of the anvil having a series of circular grooves and the sides of the anvil being spaced apart and substantially conforming to the walls of the chamber 12.

I have further found that by making a reproducer substantially as shown, that I produce a very clear reproduction of the record which reproduction is not marred by scratching noises which are often noticeable when an ordinary reproducer is used.

I claim as my invention:

1. In a phonograph reproducer, the combination of: a supporting structure; a main diaphragm closing the front of a sound chamber formed in said structure; means for attaching a tone arm to said structure; a stylus holder flexibly mounted on said structure and having its upper end in contact with said diaphragm; means for securing a needle in the other end of said stylus holder; a cross lever engaging said stylus holder; a drum diaphragm against which one end of said cross lever rests; and pivots parallel to said stylus holder upon which said cross lever is supported.

2. In a phonograph reproducer, the combination of: a supporting structure; a main diaphragm closing the front of a sound chamber formed in said structure; means for attaching a tone arm to said structure; a stylus holder flexibly mounted on said struc-

ture and having its upper end in contact with said diaphragm; means for securing a needle in the other end of said stylus holder; a cross lever engaging said stylus holder; a drum diaphragm parallel with said main diaphragm against which one end of said cross lever rests; and pivots parallel to said

In testimony whereof, I have hereunto set 10
my hand at Los Angeles, California, this
16th day of April 1921.

MILON J. TRUMBLE.
